US0D1023991S

(12) **United States Design Patent** (10) Patent No.: **US D1,023,991 S**
(45) Date of Patent: ** Apr. 23, 2024

(54) **TELEVISION APPARATUS**

(71) Applicant: **Kamara Werbe und Kommunikations GmbH**, Vienna (AT)

(72) Inventor: **Stefan Pani**, Vienna (AT)

(73) Assignee: **KAMARA Werbe und Kommunikations GmbH**, Vienna (AT)

(**) Term: **15 Years**

(21) Appl. No.: **35/515,560**

(22) Filed: **Oct. 25, 2022**

(80) **Hague Agreement Data**

Int. Filing Date: **Oct. 25, 2022**

Int. Reg. No.: **DM/224519**

Int. Reg. Date: **Oct. 25, 2022**

Int. Reg. Pub. Date: **Nov. 11, 2022**
